DISPLAY FIGURE

Elwood H. Sheppard, Bellvue, Colo.

Application August 11, 1949, Serial No. 4,414

Term of patent 3½ years

(Cl. D29—23)

To all whom it may concern:

Be it known that I, Elwood H. Sheppard, a citizen of the United States, residing at Bellvue, in the county of Larimer and State of Colorado, have invented a new, original, and ornamental Design for a Display Figure, of which the following is a specification, reference being had to the accompanying drawing forming a part thereof.

Fig. 1 is a side perspective view of a display figure showing my new design; and

Fig. 2 is a front perspective view thereof.

I claim:

The ornamental design for a display figure, as shown.

ELWOOD H. SHEPPARD.
